UNITED STATES PATENT OFFICE.

GEORGE F. SIMONDS, OF FITCHBURG, MASSACHUSETTS.

MAKING METAL-ROLLING DIES.

SPECIFICATION forming part of Letters Patent No. 352,367, dated November 9, 1886.

Application filed April 8, 1886. Serial No. 198,257. (No model.)

To all whom it may concern:

Be it known that I, GEORGE F. SIMONDS, of Fitchburg, Worcester county, Massachusetts, have invented a new and Improved 5 Method of Making Dies for Making Rolled 10 Forgings; and I hereby declare the following to be a full, clear, and exact description of the same, reference being had to the accompanying drawings, making part of this specification, in which--

Figure 1 is a perspective view of the die after the first step of manufacture. Fig. 2 is a perspective view during the second step. Fig. 3 illustrates the die during the third step, 15 and the character of the cutting-tool applied. Fig. 4 illustrates the die completed. Fig. 5 illustrates a modification of a completed die wherein the working-faces are sectional and the idle portion of the face entirely removed. 20 My invention relates to dies to be used in the forging-machine upon which a patent was issued to me on June 9, 1885, No. 319,752, and has for its object to provide a cheap yet perfect way of constructing said dies.

25 To this end my invention consists in a novel method of forming the die-faces, by first cutting the face of the die in the configuration of more or less of the cross-sectional area of the article to be formed to make a shaping and 30 finishing surface, then cutting the side walls of the die on diagonal lines to the horizontal and vertical planes of the die to form spreading and reducing surfaces, and finally removing the surplus metal or "idle-face" 35 portions of the die, to prevent unnecessary friction.

In order that those skilled in the art may make and use my invention, I will proceed to describe the manner in which I have carried 40 it out.

For purposes of illustration in this specification I have selected a die designed to roll a conical steel shot; but whatever the variation of the face of the die may be the method of 45 making is the same. The entire shape is given to the die by means of a planer.

I first take the steel plate A from which the die is to be made and after dressing off the bottom and sides plane throughout its length 50 a shape conforming to one-half of the article to be forged, thereby making a form, *a b c d*, constituting the shaping and finishing surface

of the die. To make the reducing and spreading surfaces *f* and the plain blank-supporting surface *i*, I use a straight broad-faced tool, *e*, 55 and place it in the holder with its cutting-edge at such an angle to the bed of the planer as to give the required angle to the reducing and spreading surfaces of the die. I then locate the die at such an angle to the planer-bed that 60 in its passage the tool shall remove the metal from the point *x* to the central point, *c*, of the forming-surface at one end and the outer point, *b*, of the forming-surface at the other end of the die, the depth of the cut being such as to 65 make the distance between the blank-supporting surface *i* and the corresponding surface on the opposite die-face a trifle more than the size of the bar to be forged. After the foregoing step there remains in the walls of the die outside of its interior working-lines a quantity 70 of surplus metal, idle-face, not necessary to successful forging, and calculated to produce frictional distortion of the work. To remove this I place the cutting-edge of a tool, *g*, at an 75 angle nearer a perpendicular than the angle of the reducing and spreading surfaces, as seen in Fig. 3, and locate the die on the planer-bed, so that the surplus metal may be cut away, 80 leaving the reducing and spreading surface at such a width as to best facilitate its practical working. The reducing and spreading surface on the other side of the die is brought to shape, and the surplus metal removed in the same manner.

85 It is evident in the working of these dies that when the forming-surface has completed its work at any given point said forming-surface from that point to the finishing end of the die is unnecessary and at times objectionable, 90 in that it causes unnecessary friction, and I avoid this by removing within the interior lines of the die those portions of the forming-surfaces between the terminal end of the die and the point where the forming-surface has completed its work. This is done by cutting such idle face in proper lines diagonal to a horizontal plane, and is particularly well illustrated in the modification shown in Fig. 5, where I have illustrated a die made in sections A' A² to A⁹ A¹⁰ A¹¹. In this instance the work near the base of the shot (its greatest diameter) is completed substantially by the time the die has passed the work as far as sections A⁹ 95 100

and A¹⁰, and from this point to the finishing end of the die the surplus metal is cut away or gradually diverging, as seen at n n, and the completed portions of the work do not add to the friction of the passing dies.

Having thus described my invention, what I claim as new, and desire to secure by Letters Patent, is—

The method herein described for making dies for making rolled forgings, consisting, essentially, in first forming in the die-blank a sur-

face corresponding to and the converse of the cross-sectional form of the article to be produced, forming the spreading and reducing surfaces by a cut diagonal to both planes of the blank, and finally removing the surplus metal or idle-face portions, substantially as set forth.

GEO. F. SIMONDS.
